(57) **CLAIM**

The ornamental design for a mainframe for a dual-robot substrate processing system, as shown and described.

DESCRIPTION

FIG. 1 is a front, top perspective view of a mainframe for a dual-robot substrate processing system in accordance with the present design.

FIG. 2 is a left side elevational view of the present design.

FIG. 3 is a right side elevational view of the present design.

FIG. 4 is a front elevational view of the present design.

FIG. 5 is a rear elevational view of the present design.

FIG. 6 is a top plan view of the present design.

FIG. 7 is a bottom plan view of the second embodiment of the present design; and,

FIG. 8 is a front, top perspective view of the present design, showing unclaimed components attached thereto.

The broken lines shown in the figures are directed to unclaimed portions of the mainframe and/or unclaimed components attached to the mainframe that are for illustrative purposes only and form no part of the claimed design.

1 Claim, 7 Drawing Sheets
